UNITED STATES PATENT OFFICE

BERTRAM VERNON RADLEY, OF SHALDON, NEAR TEIGNMOUTH, ENGLAND

APPLIANCE FOR GOLF PRACTICE

Application filed February 17, 1930, Serial No. 428,982, and in Great Britain March 1, 1929.

This invention relates to appliances for golf practice of the type in which a plurality of balls are fed in succession to position for striking.

5 This invention has for its object to provide an appliance for use in practicing golf shots of any length from drives to putts, the said appliance being adapted for practice both out-of-doors and in-doors and is of simple 10 construction and adapted for use on ground or floor level.

In accordance with one aspect of this invention I provide an appliance for golf practice, comprising a ball magazine, a teeing cup associated therewith and means for supplying balls to the said teeing cup one by one from the said magazine at the will of the player, the said means comprising a pivoted cradle adapted to hold a ball and 15 to be recharged automatically from the magazine together with means for rocking said cradle about its pivot so as to raise the ball and cause it to run down an inclined slope and take up its position automatically on the 20 tee.

The accompanying drawing illustrates the invention:

Fig. 1 is a plan of the appliance comprising the ball teeing device and the filling chute.

30 Fig. 2 is a vertical section of the magazine along line A—A in Fig. 1.

Fig. 3 is a vertical section of the flat arm along the line B—B in Fig. 1.

35 Fig. 4 is a vertical section of the filling chute along line C—C in Fig. 1.

Mounted on a base board, table or plate 2 in brackets 2' is a magazine 3 which extends lengthwise throughout a part of the base 2 and is inclined down from the rear or ball-feed 40 and open end 4 of the magazine. In front of the forward end 5 of the magazine, which is thereat also open and beneath a hinged part of the magazine 3', is a cradle 6 which is adapted to tilt lengthwise on journals or 45 trunnions 7 supported in bearings 8 at the respective sides of the cradle. The end 9 of the cradle which is next to the end of the magazine aforesaid is cupped or dished. At the 50 other end 10 the cradle is shaped to form an open-ended duct. Between the front end of

the cradle and its pivots a lever 11, which is preferably integral with the cradle, extends out laterally therefrom, and is preferably bent.

On the part of the base which is forward 55 of the cradle are fixed a pair of bars 12 spaced apart thus serving as a runway and side guards for the balls as hereinafter set forth. Base 2 has a handle 12'.

Pivotedly or hingeably connected to the 60 base at 13, near the front end thereof, is a flat arm 14, preferably of wood lined with metal for durability, which may be detachable. This arm 14 lies, when the appliance is laid down for use, approximately at a right 65 angle to the base 2 against the end of which one side of the said arm abuts. The arm can be turned to lie alongside the base for packing purposes.

Immediately opposite the front end of the 70 base, the surface of the arm is cupped, to form a tee circle 15, the centre of the cup being approximately in the centre line of the arm. In the bottom and at the centre of the cup is a round hole or cavity 16, and 75 dipping down to this hole are depressions 17, 18, 19, 20, disposed in cruciform and converging on the hole, two being lateral and two longitudinal. Of these depressions the lateral one 19 situated at the outer or 80 further side of the central hole is bordered by a V-pad stop or cushion 21. The centre line of the V-pad 21 is also on the same centre line as that of the magazine 3, that is 85 slightly to the right of the centre line of the tee 15. This gives the ball 23 a slight spin after striking and moving back from the pad and this spin tends to prevent the pad from being over-run. Between each side of the arm and the hole in the cup are 90 holes or cavities 22 provided in the lateral depressions. The recess may be either part of the base board or be formed by a pad let into that board.

The cup or the tee circle 15 so shaped and holed constitutes a substitute for the ordinary tee and is a nest for the ball 23 to settle in preparatory to being struck and shot out by the player. The depressions 17, 18, 19, 20, aforesaid give freedom to the ball to 100

rock or oscillate before coming to rest over the hole or cavity 16 in the centre of the tee circle.

Holes 20', 20', are provided for pegging the magazine to the ground.

The method for working with the appliance is as follows:

The magazine 3 and cradle 6 are so arranged that the centre line, passing through 10 the magazine, cradle, and between the guiding bars or strips 12, when produced, does not pass through the centre line of the hole 16 but is slightly to the right of it.

A plurality of balls is charged into the 15 magazine at the feed end 4 thereof. The leading ball drops into the cradle 6 which is tilted down at its rear end 9 and raised at the forward end 10, the ball remaining stationary and holding back the next ball to

20 follow, due to the disposition and shape of the rear part of the cradle. The side lever 11 of the cradle is next depressed by the player, with his golf club head, and the cradle is thereby tilted down at the forward end.

25 The leading ball runs out forward along the runway 12 into the tee circle 15 of the arm 14 aforesaid. The stop or cushion 21 on the outer side of the tee circle 15 prevents the ball from passing out of the said

30 circle and the ball comes to rest, as above set forth, in position for striking. As the leading ball passes out of the cradle 6, the latter tilts back to normal position and receives at its rear end the next ball in succession after

35 it has been temporarily held back by the tail of the cradle. The action is repeated in respect of each ball coming down the inclined magazine.

In making the shots, the balls freely leave 40 the tee circle in the line of play and, as the formation of the "tee" recess is such as to cause the balls to come to rest correctly over the central hole 16 even when the appliance is not resting on a horizontal surface, but on

45 ground causing it to be tilted to the right, the left, forwards or backwards, shots can be made from uphill and downhill lies and also those where the ball is above or below the feet of the player.

50 The appliance can therefore, be used to practice shots of any kind except those from unusual lies and from bunkers, provided the ground under the pivoted arm is free from hillocks and un-evenness and the base plate 55 also has a sufficient amount of contact with

the ground for the appliance to stand firmly.

The supply of balls to the magazine 3 is renewed as desired. This can be done directly by hand or through the agency of a means applied at the feed end 4 of the magazine 3. 70

As an example of such a means, an inclined filling chute 24 may be employed, one end 25 of such a chute resting on the ground or floor, and the other end 27 sloping up in the direction of the rear or feed end of the magazine 3 whereat the chute is provided with a tray 28 having a central hole 26 below which is disposed an inclined chute 26' which may be detachably hooked to the magazine 3. The tray 28 is bordered at the back and rear end by an upwardly extending barrier 29, preferably adjustable vertically by a pin and slot device 29'. The chute 24 is suitably supported by vertical legs 25', the walls 24' of the incline are carried only halfway up the incline, the upper halves being turned down to give stiffness to the upper portion. The chute 26' leads at its forward end into the magazine 3. 85

With this adjunct the balls are shot up the 90 chute 24 from the ground and pass thence into the magazine 3. This obviates stooping to refill the magazine.

Variations in the constructional details and arrangements of parts may be made, both in respect of the main appliance and of an adjunct of a filling chute and also in respect of the putting arrangements without departing from the spirit of the invention. 95

What I claim and desire to secure by Letters Patent is:—

An appliance for golf practice comprising a ball magazine, a teeing cup associated therewith and means for supplying balls to the said teeing cup one by one from said magazine at the will of the player, the said means comprising a pivoted cradle adapted to hold a ball and to be recharged automatically from the magazine together with means for rocking said cradle about its pivot so as to raise the ball and cause it to run down an inclined slope and take up its position automatically on said tee, in combination with an eccentrically positioned stop adjacent said tee against which the ball is adapted to strike when delivered from said pivoted cradle in order to impart a spin to the ball on contacting with said stop. 105

In testimony whereof, I affix my signature.

BERTRAM VERNON RADLEY.
